TELEVISION APPARATUS

Arno Zillger, Narberth, Pa., assignor, by mesne assignments, to National Television Corporation, Wilmington, Del., a corporation of Delaware

Application August 10, 1932, Serial No. 628,159

8 Claims. (Cl. 178—6)

This invention relates to television apparatus and particularly to a scanning device to be used therewith.

One of the objects of the invention is to provide a scanning device for a television apparatus which operates by reflection.

Another object of the invention is to provide a reflecting scanning device in which the effect of the operating light upon any surfaces of the device other than those doing the actual scanning, is not deleterious to the production of accurate images.

Still another object of the invention is to provide a reflecting scanning device in which all surfaces other than the active surfaces reflect light away from the observer.

Other objects and objects relating particularly to the construction and assembly of the various parts will be apparent as the description of the invention proceeds.

Several embodiments of the invention have been illustrated in the accompanying drawings, in which:

Fig. 1 is a side elevational view of a receiving television apparatus embodying the invention;

Fig. 2 is a sectional plan view of the drum taken on the line 2—2 of Fig. 1;

Fig. 3 is an enlarged sectional plan view of a portion of the drum;

Fig. 4 is a sectional elevational view taken on the line 4—4 of Fig. 3;

Fig. 5 is a perspective view of one of the plates of the drum;

Fig. 6 is a sectional end view through one of the plates taken on the line 4—4 of Fig. 3 and shown with a modulated light source; and

Fig. 7 is a perspective view of another form of plate which may be used.

Referring now more specifically to the drawings, a television receiving apparatus is illustrated in Fig. 1 in which a light source 10 has an envelope consisting of two small bulbs 11 and 12 joined together at their tips or rounded ends by a relatively long tube 13. The bulbs 11 and 12, as well as the tube 13, may be made of glass, quartz, or other transparent material used extensively for electric lamp bulbs. The bulb 11 has an inturned press 14 which supports a cup-shaped anode 15 mounted on a lead-in wire 16, while the bulb 12 has an inturned press 17 which supports a cathode 18 upon a lead-in wire 19. The anode 15 may be formed of any desired metal, such as nickel, and the cathode 18 is preferably formed of a roll of nickel gauze although other metals such as Swedish iron and tantalum

may be used. A disc 15a of mica or other insulating material may be positioned against the outer end of the anode 15, a short connecting rod 16a which may be welded to the anode passing through a hole in the disc. The support rod 16 may be welded to the rod 16a, thus supporting the anode and securing the disc in position. The disc may be large enough to almost touch the walls of the bulb and tends to prevent discharge from forming on the rod 16 adjacent the 10 press.

The cathode 18 is preferably provided with as large a surface as possible, and hence it may be formed of a roll of wire mesh 9 or 10 inches long by about an inch wide. This strip of mesh is wound up and attached to a short support rod 19a which may be in turn welded to the lead-in wire 19. A disc 18a similar to the disc 15a described above, may be mounted on the rod 19a and held against the cathode by the support rod 19. This disc prevents undue discharge on the rod 19 and heating of the press.

The lamp may be filled with an ionizable gas, such as neon, or mixtures of neon and mercury vapor may be used with good results. The pressure of the gas may be in the neighborhood of 15 mm. of mercury or under. When a current in the neighborhood of 100 milliamperes is allowed to flow through this lamp at a pressure of from 600 to 1500 volts, a discharge occurs between the anode 15 and the cathode 18 passing through the narrow tube 12. This discharge is very intense and is easily modulated while the color depends largely on the combination of gases used, the mixture of neon and mercury vapor producing a bluish white light. This lamp while extremely effective in the apparatus to be described, actually forms no part of my invention. Other light sources which produce a line of light and which may be modulated in accordance with an incoming television signal may be used in place of the one just described.

A radio receiving set 20 may have its output connected respectively by means of wires 21 and 22 to the lamp lead-in wires 16 and 19. Where a direct wire television system is used the radio receiving set would, of course, be replaced by an amplifier.

In order to insure starting the lamp, I prefer to provide a high tension coil 23 having a secondary winding 24 and a primary winding 25 in series with a battery 26, a switch 27, and an interrupter 27a. The secondary winding may be connected between the wires 21 and 22 by means of wires 28 and 29 and a spark gap 30 50 55

may also be connected in series with the winding to prevent the flow of the lamp operating current therethrough. In starting the lamp the switch 27 is momentarily depressed which causes 5 high tension current to produce a discharge within the lamp which when once started will be maintained by the output of the radio set.

The present invention relates particularly to the scanning device which comprises a drum 31 10 rotatably mounted on a vertical shaft 32 rotated by a motor 33 which is adapted to run in synchrony with the speed of the motor running the transmission set. If the receiver is used on the same power circuit as the transmitter, a synchronous 15 motor will accomplish this result, but if the circuit is different from that used by the sending apparatus, a suitable synchronizing device (not shown) should be used to keep the motor 33 running in synchrony with the motor 20 of the transmitting set.

The drum 31 comprises a plurality of plates 34 which may be made rectangular as indicated in Figs. 2 and 5, and are each provided with a central hole 34a to fit over the shaft 32 and a 25 reflecting edge 35 which may lie in a plane perpendicular to the surface of the plates. These plates are arranged in a stack with the reflecting edge 35 of each successive plate turned at a slight angle with respect to the plate beneath it 30 so that the reflecting edges form a spiral around the circumference of the drum, with equal angles between adjacent edges. Where an image is formed of sixty lines, as has been the usual practice heretofore, it is necessary to provide 35 sixty reflecting edges, and hence there will be sixty plates and the angle between every two plates will be six degrees (6°) so that one complete rotation of the drum will produce one complete scanning of the image. This construction 40 is shown and described in the patent to Gardner, No. 1,753,697, wherein the other edges of the plates are described as coated with a black paint to prevent reflection therefrom.

I have found that no matter how carefully the 45 other edges of the plates are coated with light-absorbing paint, there is still some reflection from these surfaces which give rise to distortion of the image produced or at least detracts from its clarity. I have found that this difficulty can 50 be entirely eliminated by forming the other long edge 36 of each plate and the two ends 37 and 38 in planes which are not parallel with the axis of the drum but lie at an angle with the axis, so that the surfaces slope towards the axis at the 55 lower end of the drum, as clearly indicated in Figs. 1, 4, 5 and 6 of the drawings. While it may be preferred to provide these other edges with reflecting surfaces, this is not absolutely necessary, but they should at least be smooth so as 60 not to disperse the light falling upon them.

While the light rays from the line of light reflected by the surfaces 35 of the plates are redirected to the eye of an observer who stands so that his eye is about midway between the top and 65 bottom of the drum, all of the other surfaces 36, 37, and 38 will reflect light downwardly as clearly indicated in Fig. 6, so that these surfaces will appear absolutely dark and nothing but the image reconstructed by the reflecting surfaces 35 in 70 conjunction with the modulated light will appear to the observer.

As the plates 34 are necessarily thin, I provide a heavier plate or bar 39 on the top of the stack and another 40 on the bottom. The lower bar 75 40 may rest on a washer 41 which in turn may

rest on a shoulder 42 formed on the shaft 32 while the upper bar 39 may be pressed down upon the plates by a washer 43 and a nut 44 threaded on the end of the shaft.

It is very desirable that the plates be very accurately positioned with respect to each other in order to get good results, and I have found that to depend on the pressure of the nut 44 to hold them in position has disadvantages in that the plates tend to warp and so to distort the image. 10 I prefer to fasten each plate, with respect to angular movement about the shaft, to the plate above and below it and to this end I provide a pair of holes 45 and 46 in one end of each plate and a similar pair of holes 47 and 48 in the other end. 15 These holes are on a circle about the central hole 34a and are spaced equally from the center line of the plate in such a manner that the angle formed with the center of the plate is 6°. This angle would, of course, vary if more or less plates 20 were used, sixty (60) being the number chosen for purposes of illustration.

The plates are placed on the shaft one at a time, the second one being turned so that the hole 46 therein coincides with the hole 45 in the first plate and the hole 48 coincides with the hole 47 in the first. A pin 49 is then inserted through the holes 46 and 45 in the second and first plate respectively and another through the holes 48 and 47 in the second and first plate. These pins may be slightly shorter than twice the thickness of one plate but are made to snugly fit the holes 26 as to keep the plates perfectly positioned. The first plate may lock with the bar 40 in the same manner as may also the upper plate with 35 the bar 39.

The plates of the drum have been described above as being rectangular in shape. The invention is not to be limited, however, to rectangular plates as any number of sides may be used 40 as for instance the triangular plate 50 shown in Fig. 7, the edge 51 of which is perpendicular to the surface of the plate and forms the active reflecting edge, while the edges 52 and 53 are formed at an angle so that they will reflect light 45 away from the observer. The plates may also be formed with curved instead of straight edges, or may be made like a disc with one flat edge and the rest in the form of a circle. This edge may also be formed at an angle so that any light reflected thereby will be directed away from the 50 line of observation.

It will be seen from the above that I have provided a reflecting scanning device for a television apparatus by means of which the clarity of the 55 image has been greatly improved as it eliminates any possibility of extraneous light affecting the image.

In the drawings a receiving television apparatus is disclosed, but it is obvious that the scanning drum of the transmitting apparatus may be similarly constructed and the invention is intended to cover both sending and receiving devices.

Many modifications of the invention may be 65 resorted to without departing from the spirit thereof, and I do not desire to limit myself to what has been shown and described except as such limitations occur in the appended claims.

What I desire to claim is:

1. A television scanning device comprising a plurality of plates arranged in a stack and rotatable about the axis of said stack, one edge only of each plate being used for scanning a picture, said edge having a high reflecting surface at a 75

- uniform angle to the axis of said stack and adapted to form one line of the picture and the reflecting edges of successive plates being spaced angularly around the axis of said stack, all other edges of said plates being formed at a different angle to the axis of said stack, said angle being such that light is directed from said other edges outside the field of vision as defined by said highly reflecting surfaces.
5. In a scanning drum for a television apparatus a plurality of rectangular plates forming a helix completely about the axis of the drum, arranged in a stack rotatable about the axis thereof, each of said plates having one long edge only adapted to be used for scanning a picture, said edge being highly polished and lying in a plane bearing the same angular relation to the axis of said stack that the planes of the same edges on all the other plates bear to said axis, and all 10 edges on said plates not functioning to produce a portion of the picture having such relation to said axis that light is directed therefrom outside the field of vision as defined by said highly polished edges.
15. In a scanning drum for a television apparatus, a plurality of rectangular metal plates arranged in a stack and rotatable about the axis thereof, one long edge only of each plate being used for scanning a picture, said edge being highly polished and lying in a plane having a predetermined angle with the axis of said plates, said plates being so mounted that the reflecting edges thereof form a 360° helix around said drum with equal angular spacing therebetween, all edges of 20 said plates not functioning to produce a portion of the picture having such an angular relation with respect to said axis that light is directed therefrom outside the field of vision as defined by said highly polished edges.
25. In a scanning drum for a television apparatus, a rotatable drum comprising a plurality of stacked plates forming a helix completely about the axis of the drum, each of said plates having one edge only to be used for scanning a picture, said edge being polished and having a predetermined relation to the axis of said drum and functioning to produce a portion of the picture and all edges which do not function to produce a portion of the picture having such a relation to said axis 30 that light is directed therefrom outside the field of vision as defined by said polished edges, and a long narrow light source spaced from said drum and substantially parallel to the axis thereof.
35. In a television receiving apparatus a rotatable drum comprising a plurality of stacked plates, each of said plates having one edge only to be used for scanning a picture, said edge being polished and having a predetermined relation to the axis of said drum, said plates being so positioned that the reflecting surfaces form a helix 5 around said drum with equal angular spacing, all other edges of said plates having such an angular relation with respect to the axis of said drum that light is directed therefrom outside the field of vision as defined by said polished edges, and 10 a long narrow light source spaced from said drum and substantially parallel to the axis thereof.
40. A scanning drum for use in television comprising a plurality of stacked plates, each plate having one edge only which is used for scanning a picture, such edge having a reflecting surface, the plane of which bears a predetermined angle to the axis of said drum, and a second reflecting edge on each plate having an angle to the axis of said drum such that light is directed therefrom outside the field of vision as defined by said first mentioned reflecting surfaces, the number of said plates being sufficient to permit formation of an optical image on said drum without the interpolation of an optical system between the 15 drum and the point of observation.
45. A scanning drum for television use comprising a plurality of plates arranged in a stack, one edge only of each plate being used for scanning a picture, said edge being reflecting and lying in a plane having a predetermined angle to the axis of said drum and corresponding to one line of a picture to be reproduced, and all other edges of said plates being also reflecting but lying in planes having an angle to said axis such that 20 light is directed therefrom outside the field of vision as defined by said first mentioned reflecting edges, the reflecting edges lying at said predetermined angles to the drum axis producing a 25 360° helix.
50. A television scanning device comprising a rotating drum, a plurality of reflecting surfaces on said drum arranged in a successive helix completely around the circumference thereof and in planes substantially parallel to the axis of said drum, there being one surface only used for scanning the picture, such surface forming one line of the picture, and a plurality of other reflecting surfaces arranged around the circumference of said drum and lying in planes which are at an 35 angle to the axis thereof, the angle being such that light is directed from said second mentioned reflecting surfaces outside of the field of vision as defined by said first mentioned surfaces.

ARNO ZILLGER. 55
